UNITED STATES PATENT OFFICE.

LOUIS CYWAR, OF ELIZABETH, NEW JERSEY.

LIFE-PRESERVER.

1,111,299.

Specification of Letters Patent. Patented Sept. 22, 1914.

Application filed May 20, 1914. Serial No. 839,783.

To all whom it may concern:

Be it known that I, LOUIS CYWAR, a subject of the Emperor of Austria-Hungary, residing at Elizabeth, in the county of Union 5 and State of New Jersey, have invented certain new and useful Improvements in Life-Preservers, of which the following is a specification.

This invention relates to certain new and 10 useful improvements in life preservers.

An object of the invention is to provide a life preserver that may be easily and quickly attached to the body of the wearer and will, with surety, hold the head and shoulders 15 above the water.

A further object of the invention is to provide a life preserver employing a body harness, adapted to detachably support a plurality of tanks from which the air has been 20 exhausted.

My invention also contemplates the use of inflated rubber bags in lieu of the tanks before mentioned.

With the above and other objects in view 25 that will appear as the nature of the invention is better understood, the same consists in the novel construction, combination, and arrangement of parts to be hereinafter more fully described and then claimed.

30 In the accompanying drawing which shows the preferred embodiment of my invention and to which reference is had herein by like characters designating corresponding parts:—Figure 1 is a perspective view of 35 the life preserver, and, Fig. 2 is a detail sectional view of a portion of an inflated bag, constituting a modification.

It is the object of the present invention to provide a life preserver employing a body 40 harness which may be easily and quickly secured to the body of the wearer, and with this object in view, I provide a pair of transversely-arranged body straps 5 and 6 spaced one above the other and having a suitable 45 buckle connection 7 at the ends thereof. Shoulder straps 8 are provided and are secured at the rear ends to the transverse strap 6 at the point 9, the forward ends of the shoulder straps 8 being suitably apertured

for engagement with the buckle 10 secured 50 adjacent the ends of the strap 6. In position on the body, the upper strap 6 is arranged to lie beneath the arms with the lower strap 5 a suitable distance beneath the same, with the meeting ends of the several straps before 55 mentioned secured in a well-known manner.

The harness above described is adapted to detachably support a plurality of tanks or other receptacles 11 of any suitable shape, but preferably of a contour as disclosed by 60 the drawing. These tanks or receptacles 11 may be made of any suitable material, such as aluminum or other material light in weight, and it is my object to exhaust the 65 air from these tanks to enhance the buoyancy thereof. The lower ends of the tanks 11 are provided with stoppers or plugs 12 which may be removed to permit the tanks to be 70 drained of water should the same become broken or otherwise injured.

The tanks 11 are provided with staples 11' 75 adapted to be received on the straps 5 and 6 and to move freely thereover, the staples 11' forming the connection between the harness and the tanks.

A modification of the tank 11 as shown in Fig. 2 consists of the rubber bag 13 provided with the valve 14 by which the same may be inflated. Any suitable fastening means may be carried by the rubber bag 13 by which the 80 same may be secured to the straps 5 and 6 in a manner similar to the staples 11'.

It is believed that from the foregoing description of the apparatus, the operation 85 thereof will be readily apparent, and while I have shown and described the preferred embodiment of my invention, I do not wish to confine myself to the exact details of construction shown, as various forms, modifications and arrangement of the parts may be 90 had without departing from the spirit and scope of the invention as claimed.

What I claim as new is:—

In a life preserver, a body harness, said body harness comprising a pair of transverse straps provided with detachable connections at their ends, a pair of shoulder straps permanently connected at their rear 95

ends to the upper strap and detachably-connected at their forward ends to said upper strap, and buoyant tanks each provided on its inner side with vertically-aligned staples 5 aligned with said transverse straps to maintain said tanks in upright parallel relation upon the wearer's body.

In testimony whereof I affix my signature in presence of two witnesses.

LOUIS CYWAR.
